SPOUT STRUCTURE

Guy O. Conner, Wheeling, W. Va., assignor to
Wheeling Steel Corporation, Wheeling, W. Va.,
a corporation of Delaware

Application September 20, 1938, Serial No. 230,770

5 Claims. (Cl. 221—23)

This invention relates to spout structures, and particularly spout structures for containers. In certain of its more specific aspects the invention relates to spout structures especially adapted for use with sheet metal shipping containers. Still more specifically, the invention has to do with spout structures especially adapted for use with coated containers, which spout structures are themselves desirably coated.

the pouring portion of the spout to extend non-coaxially with respect to the base portion of the spout, the construction of a one-piece spout of suitable shape entails disadvantages which are commercially insurmountable. The cost of a one-piece spout of substantially the shape of a spout which can be made in accordance with the present invention is prohibitive.

I provide a multi-part sheet metal spout structure adapted after permanent assembly of its parts to be coated with a substance requiring subjection of the spout structure to temperatures so high as to deleteriously affect soldered joints, which comprises sheet metal spout parts permanently connected together, the means permanently connecting the spout parts together being resistant to temperatures substantially higher than temperatures which would deleteriously affect soldered joints. For example, the parts of my spout may be connected together by crimping or seaming or they may be connected together by welding. Preferably one or more of the parts of the spout structure is drawn to avoid side seams, although side seams may be employed if they are self-sufficient without soldering, or they may be welded.

I provide a novel form of spout having a sheet metal base part of relatively great cross-sectional dimension and a sheet metal pouring part of relatively small cross-sectional dimension, the pouring and base parts being in communication and connected together in non-coaxial relationship. The base part is preferably of generally dome shape and the pouring part preferably enters the base part adjacent the top thereof. The spout structure preferably has adjacent its bottom or base an outwardly extending annular flange thereabout, and an annular gasket is placed against a face of such flange, and at least part of the outer portion of the flange is preferably turned about the outer edge of the gasket whereby to hold the gasket in place. This latter provision is of particular advantage in connection with coated spouts when the gasket is positioned against the face of the flange remote from the lip or pouring extremity of the spout so as to seal the spout structure to a container in operative position. When the relatively thin sheet metal employed in making spouts of the character in question is sharply bent after having been coated there is danger that some of the protective coating material may come off due to the bending, but as the bent portion of the spout is at the outer periphery of the gasket and the gasket is sealed to the container.

Consequently, the soldered spouts heretofore commonly used are not suitable for coating with coating substances requiring subjection of the spout to temperatures above 350° F., and I provide a spout structure obviating this disadvantage of soldered spouts. Of course, a one-piece spout would obviate the disadvantage of soldered joints, but as it is customary and desirable for

within such bent portion, the contents of the container being poured out through the spout do not come in contact with the bent portion of the spout, and hence, even if a portion of the coating material comes off of the spout when it is bent, this is not detrimental.

Other details, objects and advantages of the invention will become apparent as the following description of certain present preferred embodiments thereof proceeds.

In the accompanying drawing I have shown certain present preferred embodiments of the invention, in which

Figure 1 is a central vertical cross-sectional view through a sheet metal shipping container having a spout applied thereto;

Figures 2 and 3 are detail fragmentary views to enlarged scale showing spout structures with the base flange integral with the spout body and separately connected therewith, respectively.

Referring now more particularly to the drawing, there is shown in Figure 1 a sheet metal shipping container which is designated by reference numeral 2 and which may be of usual construction. Seamed to the container 2 at 3 is a top 4, which in turn has seamed thereto at 5 an externally threaded neck 6 having an opening 7. There is provided a perforated sheet metal cap 8 whose skirt 9 is internally screw-threaded to permit the cap to screw down over the externally threaded neck 6. The cap has a circular perforation 10 for receiving a portion of the spout structure presently to be described.

The spout structure shown in Figure 1 and designated generally by reference numeral 11 comprises a lower or base part 12 which is drawn out of a single piece of sheet metal and is of generally dome shape. At its lower portion the base part 12 is cylindrical and at its upper portion it is curved inwardly as at 13 to form a portion of a dome. The spout structure also comprises a delivery or pouring part 14, which is of generally cylindrical shape and which is likewise drawn out of a single piece of sheet metal, both of the parts 12 and 14 being free from side seams. Adjacent its outer extremity or lip the pouring part 14 is externally threaded as shown at 15 and is provided with a screw cap 16 whose skirt 17 is internally threaded to enable the same to be screwed down onto the pouring part 14. The screw cap 16 has a suitable gasket 18, as well known in the art.

The base and pouring parts of the spout structure are permanently connected together so as to be resistant to temperatures substantially higher than temperatures which would deleteriously affect soldered joints. As shown in Figure 1, the base and pouring parts of the spout structure are seamed together at 19 so that the metal of the parts themselves holds them together. The spout parts may be welded together either with or without a seam.

The pouring part 14 of the spout structure is non-coaxial with respect to the base part 12 and has its axis disposed at an angle in the neighborhood of 40° to the axis of the base part. Such a structure would be very costly and difficult to manufacture in a single piece, but by making the base and pouring parts separate and connecting them together as above described I provide a spout which is economical to manufacture and at the same time may be coated with substances requiring subjection of the spout to relatively high temperatures.

At its lower or bottom portion the base part

12 of the spout structure 11 has an integral outwardly extending annular flange 20 of the sheet metal of the base part and there is positioned against the bottom face of this flange an annular gasket 21. The outer portion 22 of the flange 20 is turned about the outer edge of the gasket 21 whereby to hold the gasket in place. In the form shown the outer portion of the flange is downwardly and reversely turned so as to embrace the periphery of the gasket 21. A second or upper gasket 23 lies against the upper face of the flange 20 and surrounds the body of the spout. When the spout is in operative position it is as shown in Figure 1 of the drawing, the spout extending upwardly through the perforation 10 in the cap 8 and having the gasket 21 sealed to the container about the opening 7 as shown. The cap 8 is screwed down on the neck 6 and engages the gasket 23 which lies on top of the flange 20. The spout is reversible and may assume an inverted position as shown at 24 in dotted lines in Figure 1 when the spout is not in use and particularly when the filled container is to be shipped. When the spout is inverted the gasket 23 is sealed to the container about the opening 7 and a sheet metal disc may, if desired, be placed over the gasket 21 to close the perforation 10 in the screw cap 8. The sheet metal disc need not be employed as the spout itself is sealed by the cap 16 and hence cannot leak. If the disc is employed the cap 8 bears against the disc, which in turn bears against the gasket 21, while if the disc is not employed the cap bears directly against such gasket.

The spout structure is preferably coated with a suitable protective coating as above referred to before the gaskets are applied to it. When the outer portion of the flange 20 is bent to enable holding of the gasket 21 in place some of the coating material may come off. As the very purpose of the coating material is to protect the contents of the container and spout against contamination by the metal thereof, the exposure of uncoated metal of the spout would be highly undesirable if the uncoated metal were in position to come in contact with the contents. However, as the seal between the spout gasket and the container is effected interiorly of the bent portion of the spout flange, the contents of the container and spout will not come in contact with the bent portion of the spout flange, so no harm will be done even if some of the coating material comes off when the flange is bent.

The spout is, of course, coated after the base and pouring parts thereof have been connected together, and the connection as above described is such that no harm is done to the spout in coating it even at high temperatures.

Figure 2 is a fragment of a structure similar to that shown in Figure 1, showing the flange 20a as integral with the base part 12a of the spout structure and with its outer portion as shown in solid lines turned downwardly but not inwardly about the gasket 21a, which is indicated by dotted lines in Figure 2. The periphery or a portion of the periphery of the flange may be turned inwardly beneath the basket 21a similarly to the showing of Figure 1 and as indicated in dotted lines at 22a in Figure 2 if deemed necessary or desirable.

In the structure shown in Figure 3 the flange 20b is formed separately from the base part 12b of the spout structure and is connected to such base part adjacent its lower extremity as, for

example, by welding. Otherwise the structure of Figure 3 may be the same as that of Figure 2. The unitary drawn structure of Figure 2 is preferred, but a structure such as that of Figure 3, in which the flange is formed separately from the base part of the spout and connected therewith as by welding, may be employed if desired.

While I have shown and described certain present preferred embodiments of the invention, it is to be distinctly understood that the invention is not limited thereto but may be otherwise variously embodied within the scope of the following claims.

I claim:

15 1. A spout structure comprising a sheet metal spout member having thereabout adjacent its base an outwardly extending annular flange and an annular gasket lying against a face of said flange, at least part of the outer portion of the 20 flange being turned about the outer edge of the gasket whereby to hold the gasket in place.

2. A spout structure comprising a sheet metal spout member having thereabout adjacent its base an outwardly extending annular flange and 25 an annular gasket lying against the face of said flange remote from the pouring extremity of the spout structure, at least part of the outer portion of the flange being turned about the outer edge of the gasket whereby to hold the gasket in place.

3. A spout structure comprising a sheet metal spout member having a portion of the material thereof adjacent its base turned outwardly to form an integral outwardly extending annular flange and an annular gasket lying against a face 5 of said flange, at least part of the outer portion of the flange being turned about the outer edge of the gasket whereby to hold the gasket in place.

4. A spout structure comprising a drawn sheet 10 metal spout member having an integral outwardly extending annular flange and an annular gasket lying against a face of said flange, at least part of the outer portion of the flange being turned about the outer edge of the gasket where- 15 by to hold the gasket in place.

5. A spout structure comprising a sheet metal spout member having thereon a protective coating and having thereabout adjacent its base an outwardly extending annular flange and an 20 annular gasket lying against the face of said flange remote from the pouring extremity of the spout structure, at least part of the outer portion of the flange being turned about the outer edge of the gasket whereby to hold the gasket in place 25 and to maintain the contents of the spout when in use on a container out of contact with said turned portion of the flange.

GUY O. CONNER.
